COMBINED LOCKER HANDLE AND LATCH ACTUATING UNIT

Elmer T. Meidell, Aurora, Ill., assignor to Lyon Metal Products, Incorporated, Aurora, Ill., a corporation of Illinois

Filed Apr. 19, 1961, Ser. No. 64,818

Term of patent 14 years

(Cl. D10—8)

FIG. 1

FIG. 2

FIG. 3

FIG. 4

FIG. 5

FIGURE 1 is a view in perspective of a combined locker handle and latch actuating unit showing my new design;

FIGURE 2 is a front elevational view of the combined locker handle and latch actuating unit;

FIGURE 3 is a side elevational view of the combined locker handle and latch actuating unit;

FIGURE 4 is a top view of the combined locker handle and latch actuating unit; and

FIGURE 5 is a horizontal section taken along the line 5—5 of FIGURE 3.

I claim:

The ornamental design for a combined locker handle and latch actuating unit, substantially as shown.
